UNITED STATES PATENT OFFICE.

MOSES E. SHACKLEY, OF EAST LYNN, MASSACHUSETTS, ASSIGNOR TO UNITED SHOE MACHINERY CORPORATION, OF PATERSON, NEW JERSEY, A CORPORATION OF NEW JERSEY.

VAMP-TRIMMING MACHINE.

Application filed June 26, 1919. Serial No. 306,912.

To all whom it may concern:

Be it known that I, MOSES E. SHACKLEY, a citizen of the United States, residing at East Lynn, in the county of Essex and State of Massachusetts, have invented certain new and useful Improvements in Vamp-Trimming Machines; and I do hereby declare the following to be a full, clear, and exact description of the invention, such as will enable others skilled in the art to which it appertains to make and use the same.

This invention relates to trimming machines used in the manufacture of shoes and in certain respects it relates especially to machines for trimming surplus material from the upstanding flange formed by the margin of the upper of a lasted shoe. According to present-day shoemaking some of this surplus material is trimmed off prior to sewing the inseam and more is trimmed off after sewing the inseam, the first of said trimming operations being necessary to enable the looper and other instrumentalities of the inseam-sewing machine to operate without hindrance. This trimming operation is usually performed by a machine known as an upper-trimming machine. The greatest quantity of surplus material is usually at the toe where the upper is drawn in and crimped incidentally to lasting.

In lasting the toes it is customary to use a bed-lasting machine having wipers, and to bind the lasted upper around the toe end by a wire anchored to two tacks, one at each side of the shoe and about two inches from the toe. As a result of this method the marginal portion of the upper assumes a flaring formation around the toe, instead of a pleated formation as with other methods. Still referring to conditions around the toe, the marginal portion of the upper projects outwardly from the binding wire instead of lying on the insole or projecting perpendicularly therefrom. Nevertheless, at the rear of the two tacks by which the aforesaid binding wire is anchored the marginal portion of the upper assumes a substantially upright position in consequence of being fastened to the rib of the insole by staples or other temporary fasteners. A shoe having been lasted as above described is difficult to trim preparatory to sewing the inseam, one of the difficulties being due to the aforesaid flaring formation of the marginal portion of the

upper around the toe. The operatives of inseam trimming machines are obliged to work very rapidly and to tilt the shoe one way and another so that the trimming cutters may follow the curvatures of the bottom of the last. Furthermore, to insure feeding the surplus material into the field of operation, particularly that around the toe end, it has heretofore been necessary to tilt the shoe in such a way as to place the marginal portion of the upper in a substantially upright position. Consequently, in trimming around the toe end it has been necessary to depress the heel of the shoe so far that the trimming cutters, in many cases, have trimmed too closely to the insole. In such cases the shoes have been deprived of an amount of surplus material sufficient to maintain the lasted portion securely under the binding wire and to insure suitable anchorage for the inseam stitches to be subsequently sewn.

Accordingly, one object of the present invention is to provide an improved upper-trimming machine by which it will be impossible to trim the surplus material too closely, regardless of the rapidity with which the operation is performed and regardless of how or how much the shoe may be tilted while being trimmed.

A feature of the invention consists in a novel combination comprising an improved work-cage or guiding device arranged to overlap continuously and to bear on that portion of the lasted upper that lies on the margin or feather of the insole, and also to bear continuously against that portion of the upper that lies against the rib or shoulder of the insole. The illustrated machine, in which a preferred form of the invention is embodied, includes a mechanically operated feed-roll arranged so that its periphery will run on the inner side of the rib of the insole while its lower end bears on the face of the insole. The upper end of this feed-roll has a shearing edge with which an oscillatory shearing member cooperates to trim off the surplus material. The aforesaid improved work-gage is arranged to cooperate with this feed-roll to form a channel through which the marginal portion of the upper must pass, the relation of these two devices being such that whenever the shoe is tilted excessively in one direction or the other either the feed-roll or the work-gage

will serve as the fulcrum for such tilting and will increase the distance between the insole and the trimming cut. The minimum distance may be initially determined by the 5 depth of the feed-roll.

The aforesaid work-gage is preferably arranged so that it may yield away from the feed-roll to accommodate variations in the thickness of material that passes between 10 them, and is preferably urged toward the feed-roll by a spring only strong enough to insure maintaining it in overlapped relation with that portion of the upper that lies on the feather of the insole. This gage, however, is preferably incapable of moving toward or from the plane of the trimming cut, and, like the feed-roll, constitutes a positive 15 gage for preventing the feather of the insole from approaching too closely to the plane of 20 the cut.

Another feature of the invention consists in a novel formation of the aforesaid work-gage by which the flaring portions of the upper are deflected to an upright position as 25 they approach the field of operation, thus doing away with reciprocatory devices heretofore provided for this purpose.

Other features of the present invention consist in certain constructions, arrangements and combinations of parts hereinafter 30 described and claimed, the advantages of which will be obvious to those skilled in the art.

The several features of the present invention will be clearly understood from the following description and accompanying drawings in which:

Figure 1 is an elevation of the upper portion of a vamp trimming machine embodying the features of the invention in their preferred form; Fig. 2 is a detail left end elevation of the improved work guiding device or guard; Fig. 3 is an elevation on an enlarged scale of the work engaging instrumentalities of the machine, particularly illustrating the improved work guiding device or guard; Fig. 4 is a plan view partly in section of the same; Fig. 5 is a sectional view, partly in elevation, taken on the line 50 5-5 of Fig. 4; and Fig. 6 is a vertical section of the toe end of a lasted shoe of the welt type in which the pulled-over portion is held in lasted position by a binding wire, and includes dotted lines representing the 55 work-engaging elements of the trimming machine to show the operative relation of the work thereto.

The machine, as illustrated in the drawings, is provided with a work guiding device which comprises a continuously rotating vertical guide roll 4. The lower end of the guide roll is flattened for engagement with the sole 5 of a shoe placed in the machine and the periphery at the upper end 6 of the 65 guide roll constitutes a circular shearing

edge. The machine is further provided with a trimming knife 8 which is vibrated in a segmental path across the shearing edge 6. The work guiding device and trimming knives, and their actuating mechanisms, may be and preferably are the same as disclosed in the patent to Hadaway, No. 922,697 dated May 25, 1909.

The present embodiment of the invention is provided with a work guiding device 75 or guard 10 which cooperates with the guide roll 4 to properly present the projecting edges of the vamp and lining of a lasted shoe placed in the machine to the action of the trimming knives. This guiding device 80 10 comprises a shank 12 which is positioned substantially in the plane of the shearing edge 6 and substantially in line with the roll 4 transversely of the direction of feed. The shank 12 is mounted to slide in a horizontal dovetailed way 14 formed in a bracket 16 secured by bolts 18 to the frame of the machine. A boss 20 on the shank 12 is bored and tapped to form an adjustable connection with a bolt 22 which is screwed thereon and held by a lock nut 24. The bolt 22 extends through an aperture in a boss 26 on the upper side of the bracket 16 and is guided by the outer end of the wall of the aperture. The device 10 is urged toward the guide roll 4 by means of a spring 28 coiled about the bolt 22 and interposed between a collar 30 secured to the bolt and a shoulder formed by the outer end of the wall of the aperture in the boss 26. The movement of the device 10 toward the guide roll 4 under the influence of the spring 28 is limited by an adjustable stop on the outer end of the bolt, which stop comprises nuts 32 threaded on the end of the bolt and is adapted to engage the rear end of the boss 26. 95

Vertical slots 34 are formed in the bracket 16 where the attaching bolts 18 extend through it, to provide for vertical adjustment of the device 10 relatively to the trimming parts. These slots enable the device 10 to be adjusted so that it will bear on the work as shown in Figure 6.

The shoe to be operated upon is placed in the machine in such manner that the lower end of the guide roll engages the sole of the shoe, and the projecting marginal portion of the upper 35 is positioned between the periphery of the guide roll and the guiding device 10, the spring 28 permitting the latter to accommodate itself to the thickness of the work. The tension of the spring 28 is adjusted to sustain the rib 37 of the insole against the periphery of the guide roll with only sufficient force to cause the work to be 115 fed by the roll.

In order to turn up flaring portions of the marginal portion 35 so as to present them to the trimming knives during the feeding of the work, the device 10 is curved 120 130

and is provided with a deflector 36 located in advance of the trimming knives.

In using a machine constructed as herein described the device 10 continuously over-laps the margin of the shoe outside the up-standing flange of upper material and is below the plane of trimming. Since this device is incapable of upward movement or flexure it precludes the possibility of trimming the upper too closely. For example, if the operator tilts the shoe too far downwardly the device 10 becomes a fulcrum for such tilting, and the depth of the upstanding flange from its base to the line of trimming is increased. On the other hand, if the shoe is tilted too far upwardly it rocks on the roll 4, and again increases the distance between the base of the flange and the line of trimming. Consequently the result of any error in tilting the shoe will be to trim less closely to the sole, regardless of which way the shoe is tilted. Since a sufficient remainder of material is assured a greater amount of surplus material may be trimmed off than could be done safely by former machines.

Referring to Figure 6, the marginal portion 35 of the upper stands in its normal position, that is, the position it occupies before it is bent to a more upright position by the member 10. One purpose of this figure is to illustrate the normal condition of the margin 35 which has heretofore induced the operatives to tilt the shoe to rectify its position with the disadvantage of trimming too closely. Another purpose of this figure is to illustrate the correct adjustment of the member 10 for trimming a shoe of this type. In this figure the member 10 is adjusted to a lower plane in comparison with Figs. 1, 3 and 5, such adjustment being afforded by the slots 34 in the bracket 16 and also by the screw-connection at the forward end of the bolt 22. Under working conditions, when the shoe is in operative position the marginal portion 35 would be bent to an upright position by the member 10 so as to pass between the shearing elements 6 and 8. The member 8, in this figure, is not fully retracted, which accounts for the comparatively small space between its cutting edge and that of the feed-roll.

The nature and scope of the present invention having been indicated, and a machine embodying the several features of the invention in their preferred form having been specifically described, what is claimed is:—

1. An upper trimming machine comprising a guide roll arranged so that one end will engage the face of the insole of a lasted shoe while its periphery engages the inner surface of the material being trimmed, the other end of said roll having a shearing edge, a mechanically operated cutter ar-

ranged to cooperate with said shearing edge, and a trimming gage arranged to overlap continuously the overdrawn portion of the upper that lies on the margin of the insole to keep said overdrawn portion at a predetermined distance from the line of trimming when the shoe is tilted so as to lay the marginal portion of the upper against said roll. 70

2. A vamp trimming machine having, in combination, a guide roll for the vamp and lining having a shearing face at one end and its other end directed toward the surface of the sole of a shoe placed in the machine, a work guiding member immovable in a plane perpendicular to said shearing face arranged to engage the work substantially in line with the roll transversely of the direction of feed to cooperate with the guide roll in guiding the work, and a trimming knife working across said shearing face. 75

3. A vamp trimming machine having, in combination, a guide roll for the vamp and lining having a shearing face at one end and its other end directed toward the surface of the sole of a shoe placed in the machine, a work guiding member movable in a plane parallel to said shearing face to cooperate with the guide roll in guiding the work comprising a plate mounted to slide in a plane parallel to said shearing face, a spring for urging the plate toward the guide roll, and a wiper comprising an upwardly projecting member carried by the plate to turn up the projecting edges of the vamp and lining in advance of the point of engagement of the guide roll, and a trimming knife working across said shearing face. 80

4. A vamp trimming machine having, in combination, a guide roll for the vamp and lining having a shearing face at one end and its other end directed toward the surface of the sole of a shoe placed in the machine, a work guiding device to cooperate with the guide roll in guiding the work comprising a plate mounted to slide in a plane parallel to said shearing face, a spring for urging the plate toward the guide roll, and a trimming knife working across said shearing face. 100

5. A vamp trimming machine having, in combination a work guiding and shearing device having a shearing face on one side and its opposite side directed toward the face of the sole of a shoe placed in the machine, a work guiding member movable toward and from said device engaging the outside of the vamp to cooperate with said device in guiding the work, a member carried by said work guiding member to turn up a projecting edge of the vamp in advance of said device, and a trimming knife working across said shearing face. 115

6. A trimming machine comprising means for trimming surplus material from the margin of the upper of a lasted shoe, and two cooperative work-guiding members one 130

- of which is arranged to engage the insole and the inner surface of said margin and the other of which is arranged to engage continuously the outer surface of said margin and the pulled-over upper material lying on the insole, one of said members being arranged to yield away from the other but being fixed excepting in respect to such yielding.
- 10 7. A trimming machine comprising means for trimming surplus material from the margin of the upper of a lasted shoe, and two cooperative work-guiding members arranged to engage said margin continuously, 50 one against the inner surface and the other against the outer surface of said margin to present the latter in upright position to said trimming means, said members being fixed excepting that one of them is arranged to yield away from the other and one of them is arranged to rotate so as to have rolling contact with said margin.
8. A trimming machine comprising means for trimming surplus material from the up- 55 standing margin of the upper of a lasted shoe, and two cooperative work-guiding members arranged to engage the work continuously so as to bear respectively against the inside and outside of said margin, said members being fixed excepting that one of them is arranged to yield away from the other and the inside one is arranged to rotate so as to have rolling contact with said margin.
- 35 9. A trimming machine comprising means for trimming surplus material from the up- 60 standing margin of the upper of a lasted shoe, and two cooperative work-guiding members arranged to engage the work continuously, one inside and the other outside 65 said margin, said members being fixed excepting that the outside one is arranged to yield away from the inside one and the latter is rotatable so as to have rolling contact with said margin while otherwise engaging the insole.
10. A trimming machine comprising shear- 70 ing means for trimming surplus material from the upstanding margin of the upper of 75 a lasted shoe, and two cooperative work-guiding members arranged to engage the work continuously, one inside and the other outside 80 said margin, said members being fixed excepting that one of them is arranged to yield away from the other but being fixed excepting in respect to such yielding.
11. A trimming machine comprising means for trimming surplus material from the margin of the upper of a lasted shoe, a roll arranged to turn about a fixed axis so that its periphery will have rolling contact with the inner side of said margin while one end acts as an abutment for the sole, and a work-guiding member arranged to cooperate with said roll to present said margin in upstanding position to said trimming means, said work-guiding member being fixed excepting that it is arranged to yield away from said roll.
12. A trimming machine comprising a roll arranged so that one end and the periphery will bear respectively on the sole and on the inner side of the upper margin of a lasted shoe, a work-guiding member arranged to bear continuously against the outer side of said margin so as to cooperate with said roll to bend the margin to upstanding position relatively to the sole, said work-guiding member being fixed excepting that it is arranged to yield away from said roll in lines substantially at right angles to the axis of said roll, and trimming means including a knife arranged to cooperate with the edge at the other end of said roll to trim surplus material from said margin.
13. A trimming machine comprising two cooperative work-guiding members one of which is arranged to engage the inner side of the margin of the upper of a lasted shoe and the other of which is arranged to overlap continuously the pulled-over portion of the upper on the feather of the sole and to engage the outer side of said margin, and means arranged to trim surplus material from the upper material between said members.

MOSES E. SHACKLEY.
